UNITED STATES PATENT OFFICE.

FRANK S. CROWELL, OF TOLEDO, OHIO, ASSIGNOR TO THE EDWARD N. RIDDLE CO., OF
TOLEDO, OHIO, A CORPORATION OF OHIO.

DESIGN FOR AN ELECTRIC HALL LANTERN.

Application filed April 20, 1922. Serial No. 1,856. Term of patent 3½ years.

To all whom it may concern:

Be it known that I, FRANK S. CROWELL, a citizen of the United States, residing at Toledo, in the county of Lucas and State of Ohio, have invented a new, original, and ornamental Design for an Electric Hall Lantern, of which the following is a specification, reference being had to the accompanying drawing, forming part thereof.

The figure is a perspective view of an electric hall lantern, showing my new design.

I claim:

The ornamental design for an electric hall lantern, as shown.

FRANK S. CROWELL.
